UNITED STATES PATENT OFFICE

BERKELEY S. VAUGHAN, OF GENEVA, ILLINOIS, ASSIGNOR TO WHEELER SCREEN COMPANY, OF GENEVA, ILLINOIS, A CORPORATION OF ILLINOIS

ARTICLE OF FURNITURE AND HINGE THEREFOR

Application filed June 13, 1929. Serial No. 370,531.

My invention relates to articles of furniture, for example dressing tables, in which a cover or top is employed, from which depends or is supported a flexible or textile covering or curtaining. In the exemplification of my invention herein shown I illustrate a dressing table in which curtaining extends from the top to the floor throughout the entire portion of the dressing table except the back, the back being positioned for example against a wall. It may be desirable to use the space beneath the dressing table for storage, for example for shelves, and in employing the dressing table it may be desirable for the user to permit the knees to penetrate within the space beneath the top of the dressing table, as when the user is seated at the dressing table. For this reason it is desirable to provide means whereby at least a portion of the fabric side or covering of the dressing table may be moved aside. One object of my invention is to provide such means whereby the fabric side of the dressing table may be opened or moved with maximum ease and minimum disturbance. Another object is to provide supporting means for the portion of the fabric sides which is to be moved, which will permit ready movement and which will insure that the portion of the dressing table side which is so moved shall not be crushed or wrinkled. Another object is to provide supporting means whereby the movable portion of the fabric side of the dressing table shall be substantially indistinguishable from the rest when it is in closed position. Another object is the provision of improved hinged means whereby the above objects may be obtained simply, cheaply and efficiently. Other objects will appear from time to time in the course of the specification and claims.

I illustrate my invention more or less diagrammatically in the accompanying drawings, wherein—

Figure 1 is a plan view;

Figure 2 is a front elevation;

Figure 3 is a detail; and

Figure 4 is a section on the line 4—4 of Figure 2.

Like parts are indicated by like symbols

throughout the specification and drawings.

A generally indicates the top of an article of furniture which may be a dressing table. The top is mounted for example on the legs A¹, although any other suitable supports may be provided. I may if desired provide interior supports, shelves or the like, beneath the top A, which are indicated as at A². I do not wish to be limited to any specific form or configuration of the edge of the top but I indicate a front edge which is curved to approximate the so-called kidney shape, this curved edge being indicated as at A³ in Figure 1, the intermediate arcuate recess A⁴.

I provide as side finish or side protection for the illustrated article of furniture a flexible fabric indicated as at B. It may be ruffled at the top as at B¹ and secured as by the tacks B² to the edge of the top A. In order to provide access to the shelves A², or to permit the knees of the user to penetrate within the line of the edge A³ A⁴ without wrinkling the member B I provide hinged supports generally indicated as B³ and shown in Figure 3. Each such support includes a body portion B⁴ which conforms, as shown in Figures 1 and 2, to the arcuate edge A³ A⁴ and lies in the general plane of such edge, as shown in Figures 2 and 4. The body portion B⁴ is connected by a curved or offset portion B⁵ with the hinge member proper B⁶ which underlies the lower face of the top A. It is apertured as at B⁷ to receive any suitable securing member, for example a screw B⁸. Note that the pivot point is well within the edge of the top A, as will be clear from Figure 1. Note also that the hinge portion B⁶ projects along the aperture B⁷ in order to reduce the strain upon the securing member B⁸. The fabric side member B is carried out over the top portion B⁴ of the hinge support in such fashion that when the device is ready for use, with the body portions B⁴ in the full line position of Figure 1 the body portions are entirely concealed and the device gives the same impression as if the fabric side B were secured throughout the periphery of the edge of the top A. The fabric portion may be supported on the member B⁴ as by the loop or hem B¹⁰ shown in Figure 4. In order to prevent

any interference with the free movement of the supporting hinge members about their pivots I provide an intermediate portion B¹¹ of the member B which is kept free from securing means as shown in Figure 2.

5 It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

15 I claim:

1. As a new article of manufacture, an article of furniture including a top and a fabric side depending from said top, and a movable support for a portion of said fabric side pivoted to said top, the said support including a fabric supporting body lying in the general plane of the top and means for holding said support substantially horizontal at all positions, including a hinge portion extending beneath the top and secured to the lower face thereof.

2. As a new article of manufacture, an article of furniture including a top and a fabric side depending from said top, and a movable support for a portion of said fabric side pivoted to said top, the said support including a fabric supporting body lying in the general plane of the top and means for holding said support substantially horizontal at all positions, including a hinge portion extending beneath the top and secured to the lower face thereof, at a point substantially within the edge of said top.

3. In combination with a top for a piece of furniture, a pivoted support including a body portion conforming to and lying in the same plane as the edge of the top, and a hinge portion inwardly projecting therefrom, underlying said top and pivoted to the under side thereof.

4. In combination with a top for a piece of furniture, a pivoted support including a body portion conforming to and lying in the same plane as the edge of the top, and a hinge portion inwardly projecting therefrom, underlying said top and pivoted to the under side thereof, at a point substantially within the periphery of the top.

5. A piece of furniture including a rigid top structure, fabric side walls depending therefrom, a fabric front wall, means for movably supporting the front wall comprising an arm having a fabric supporting portion conforming in shape to the front edge of the top structure and lying in the same general plane therewith, said arm also having an inturned hinge portion offset below the plane of the fabric supporting portion of the arm and extending beneath the top structure, and

means pivotally securing the arm to the under side of the top structure.

Signed at Geneva, county of Kane and State of Illinois, this 10th day of June, 1929.
